UNITED STATES PATENT OFFICE.

LLOYD BLACKMORE, OF HIGHLAND PARK, AND FRED A. VOELKE, OF DETROIT, MICHIGAN, ASSIGNORS TO GENERAL MOTORS CORPORATION, OF DETROIT, MICHIGAN, A CORPORATION OF DELAWARE.

SPRING-SEAT STRUCTURE.

Application filed July 12, 1923. Serial No. 651,108.

This invention relates to seat springs, such as are used in motor vehicles, and has for an object the provision of a simple construction made up of wire and sheet metal in a manner which gives a maximum of strength and resistance with a minimum cost for material.

In one arrangement, a plurality of coil springs are arranged in transverse rows, each 10 row being supported by side members (shown as channeled to embrace the coils of the springs), which are arranged to interlock with an outwardly bent flange of an outer frame member to provide a very strong 15 joint in a simple manner. Preferably the outer frame is made up in two halves, which halves are held together by those of the cross members which come at the ends and which are arranged to bridge the joints between the ends of the half-frame members.

A further object of the invention relates to an improved method of manufacturing springs of this type by arranging the rows of coil springs as sub-assemblies, each of 25 which sub-assemblies is held together by cross frame members on opposite sides, preferably in the form of channel pieces embracing coils of the springs, and then bending the ends of the cross frame members to 30 interlock with an outwardly bent flange on the outer frame. This method of making up the seat spring makes it possible to make up the half-frame members and the sub-assemblies of the springs in advance in large 35 quantities, and then to make up the seat springs themselves as they are required, inasmuch as the final step of assembling each 40 complete spring is capable of being carried out rapidly and yet in a manner which provides a very rigid construction.

Other objects and features of the invention, including a novel construction by which there is a diagonal resilient brace between the upper and lower frame members of the 45 spring, and other novel combinations of parts and desirable particular constructions, will be apparent from the following description of the illustrative embodiment of the invention shown in the accompanying drawings, in which:

Figure 1 is a bottom plan view of a seat spring, but with only part of the coil springs in place;

Figure 2 is an end elevation of the complete spring construction; and

Figure 3 is an enlarged perspective view showing the interlocking relationship of the various parts as described above.

In the illustrated embodiment shown in the drawings there are two half-frame members 10 and 12, which in the completed assembly of the spring construction are arranged with their ends in abutting relationship. These half-frame members are connected by a plurality of sub-assemblies, each comprising a row of coil springs 14 held together by side frame members 16. Each of the side frame members is preferably of channel form, the channel embracing the edges of the coils of the springs and being crimped to hold the coils firmly as shown at 18 in Figure 3. A considerable number of these sub-assemblies, each consisting of two side frame members 16 with the coil springs carried thereby, is preferably made up in advance and in the step of finally assembling the spring construction these sub-assemblies are arranged transversely of the outer frame made of the members 10 and 12 and rigidly interlocked therewith by flattening the ends of the side frame members 16 as shown at 20 and bending them to hook over and interlock with outwardly bent flanges 22 formed on the outer frame members 10 and 12. The flanges 22 and the flattened hook portions 20 of the cross members are finally crimped securely in place as shown at 24, in Figure 3, thus forming a very strong joint without the use of separate fastenings.

In making up the complete spring structure as described, the frame members 16 at opposite ends of the outer frame 10-12 are arranged to bridge the joints between the abutting ends of the members 10 and 12 and are secured to both of the half-frame members, as for example by the use of sheet metal clips 26 (Figure 3) which may be separate pieces, but which are shown as being integral with the half-frame members 10 and 12. This provides a rigid end construction for the outer frame without necessitating welding or otherwise directly connecting the ends of the half frame members.

The upper frame 30, which is yieldingly supported from the bottom frame 10-12 by

the coil springs 14, to which it is attached by sheet metal clips 32 or in any other suitable manner, is additionally connected to the bottom frame by resilient cross members 34, 5 shown as being made of spring wire, and which are preferably integral with continuing wire cross pieces 36 which go directly across the top frame member 30 to form transverse resilient braces. The diagonal 10 braces 34 are arranged to be bowed outwardly by depression of the top frame member 30 when the seat spring is supporting a load and to resist such depression by their resilience. This provides additional support for 15 the extreme front edge of the top frame 30 which it is extremely difficult to support adequately by the use of coil springs alone.

The springs 14 of each series may, if desired, be connected at their tops by wire loops 20 or ties 38. Intermediate the tops and bottoms of these springs they may also be connected, if desired, by sheet metal channel members 40 crimped to grasp the wire coils.

While one desirable construction has 25 been illustrated, and the method of making it has been described, it is not our intention to limit the scope of our invention to that particular construction or method or otherwise than by the terms of the appended 30 claims.

We claim:

1. A spring construction comprising, in combination, a pair of outer frame members arranged with their ends in abutting relation, and spring supporting cross members arranged to bridge the joints between said abutting ends at opposite ends of the frame and connected to both of the frame members to form joints therebetween. 35

2. A spring construction comprising, in combination, a pair of half-frame members arranged with their ends in abutting relation to form an encircling frame, a row of coil springs across each end of said frame, and a sheet metal member at each end of the frame construction arranged to support the corresponding row of springs and arranged to bridge the joint between the ends of the half-frame members and connected to both of said half-frame members to form a joint 40 45 therebetween. 50

3. An end construction for a spring frame comprising abutting frame members, an inwardly opening spring-embracing channel member bridging the joint between said frame members, and sheet metal clips bent to hold the channel member and secured to both of the frame members to form a joint 55 therebetween.

LLOYD BLACKMORE.
